United States Patent Office

Des. 215,885
Patented Nov. 4, 1969

215,885

HYDRAULIC POWER UNIT

Ernest J. Svenson, 2330 23rd Ave.,
Rockford, Ill. 61101

Filed July 15, 1968, Ser. No. 12,760

Term of patent 14 years

Int. Cl. D15—99

U.S. Cl. D55—1

Fig. 1.

Fig. 2.

*Fig. 3.*FIG. 1 is a perspective view of a hydraulic power unit showing my new design;

FIG. 2 is an end elevational view as seen from the left of FIG. 1; and

FIG. 3 is a perspective view as seen from the rear of FIG. 1.

The dominant features of my design reside in the portions shown in full lines.

I claim:

The ornamental design for a hydraulic power unit, as herein shown and described.
